FIG. 1.

FIG. 6.

FIG. 2.

UNITED STATES PATENT OFFICE

2,526,119

FOUNTAIN WASHING DEVICE

William B. Cravis, New York, N. Y., assignor to
 Quaker Maintenance Company, Inc., New York,
 N. Y., a corporation of New York

Application January 19, 1949, Serial No. 71,720

4 Claims. (Cl. 15—130)

1

This invention relates to new and useful improvements in scrubbing or washing devices, and more particularly to such devices for use in washing walls, ceilings and like surfaces in conjunction with machines of the general type shown and described, for example, in United States Patent No. 2,003,847.

The principal object of the present invention is to provide a scrubbing or washing device of the type described wherein the flow of cleaning or rinse fluid to the surface being washed may be controlled and regulated at will by the user without interrupting or interfering with the washing operation.

Another object of the invention is to provide a novel scrubbing or washing device of the character set forth which is constructed and arranged to permit quick and easy interchange of the scrubbing members thereof.

Still another object of the invention is to provide a washing device of the type described having a handle structure which is readily detachable and embodies a novel valve mechanism for controlling the flow of fluid to the scrubbing member.

A further object of the invention is to provide a scrubbing or washing device embodying certain novel features of construction and arrangement which is comparatively inexpensive to manufacture and is highly efficient and effective in operation and use.

These and other objects of the invention, and the various features and details of its construction and operation, are hereinafter fully set forth and described with reference to the accompanying drawing, in which:

Fig. 1 is a view in perspective of a wall washing machine incorporating scrubbing or washing devices made in accordance with the present invention, and illustrating the manner and use thereof;

Fig. 2 is a view in perspective of a washing device made according to the present invention and showing the major parts thereof in relatively separated relation;

Fig. 3 is an enlarged fragmentary sectional view taken on line 3—3, Fig. 2;

Fig. 4 is a sectional view slightly enlarged taken on line 4—4, Fig. 2;

Fig. 5 is an enlarged fragmentary sectional view showing the construction and arrangement of the fasteners for detachably securing the washing member to the handle or body structure of the device; and

Fig. 6 is a view in perspective showing a cover-

2

ing surrounding a washing device which is used under certain washing conditions.

Referring now more particularly to the drawing, washing apparatus of the type to which the present invention relates may comprise a pair of tanks 1 and 2 adapted to contain, respectively, a mixture of water and cleaning material such as a suitable detergent and a supply of clear water for rinsing purposes. Pressure means in the form of a hand pump 3 may be provided for maintaining the liquid in the tanks 1 and 2 under desired pressure, and leading from the tanks are hoses 4 and 5, respectively, having scrubbing or washing devices 6 connected to their outer ends.

According to the present invention, the scrubbing or washing devices 6 each comprise a body member 7 in the form of a rigid plate of metal, plastic or other suitable material. Secured upon the upper face of the body plate 7 is a valve 8, the body 9 of which is secured directly to the surface of the plate 7. The valve body 9 is provided at one end with an axial bore portion 10 of relatively large diameter, an intermediate bore portion 11 of reduced diameter and a bore portion 12 at the other end of the body 9 having a diameter slightly less than the bore portion 10 but greater than that of the bore portion 11.

Threaded into the bore portion 10 of the body 9 is a fitting 13 to which is connected the outer end of say the hose 4 of the washing machine. The inner end of the fitting 13 is provided with a relatively large bore portion 14 in which is seated a coil spring 15. The spring 15 acts between an annular shoulder in the fitting 13 and the outer face of the head portion 16 of a valve element 17 normally to maintain the valve in closed position against the wall 19 of the valve body 9 as shown in Fig. 4 of the drawing. The valve 17 is provided with a stem 18 which is slidably mounted in the bore portion 11 of the body 9, the stem 18 being helically grooved as indicated at 20 to permit flow of fluid from the hose 4, through the bore portions 10 and 11, and thence outwardly of the valve body 9 through a discharge port 21 therein and a registering opening 22 provided in the body plate 7 of the device.

The other end of the valve bore portion 11 from the portion 10 is closed by a resilient washer or diaphragm 23 which seats against the shoulder provided at the inner end of the bore portion 12, and this diaphragm 23 is held in fluid-tight relation against said shoulder by means of a gland or fitting 24 that is threaded in the valve body 9, for example, as shown in Fig. 3 of the drawing. Slidably mounted within the fitting 24 is a plunger

member 25 having a head portion 26 disposed exteriorly of the valve body. Engaged with the plunger head 26 is one portion of an actuating lever 27 which, when actuated in the direction of the arrow in Fig. 4 by the operator of the machine, functions to actuate the plunger 25 inwardly of the valve body 9. In the embodiment illustrated the lever 27 has one end anchored to the valve body 9 by a pin 35 which is threaded to the end face of said body at one side of the plunger 25, and at the other side of said plunger there is secured a guide pin 36 which extends through an opening 27a in the lever and has a cross-head portion 36a constituting a stop limiting the outward or in operative position of the lever. Inward actuation of the plunger 25 as described displaces the diaphragm 23 in the manner shown in Fig. 3 of the drawing and causes the valve element 17 to be actuated to open position to permit liquid to flow through the valve and discharge through port 21 and the opening 22 in the plate 7. The helical grooves 20 in the valve stem 18 are of relatively small cross-sectional area and provide substantially a metered flow of liquid through the valve 8.

Detachably secured to the underside of the body plate 7 of the washing device is a scrubbing or washing element generally designated 28. This element 28 comprises a sponge portion 30, preferably of the synthetic or artificial type, and a backing member 31 which is provided with an opening or hole 31a therein in register with the plate opening 22. The backing member 31 preferably is a flexible material such as fabric, for example, canvas or the like, and is secured to the sponge member 30, for example, by relatively coarse stitching 32 or a suitable adhesive. The scrubbing or washing element 28 comprising the sponge 30 and backing 31 is detachably secured to the body plate 7, for example, by means of snap fasteners or the like, the inter-cooperating portions 33a and 33b of which are secured in the body plate 7 and backing member 31, respectively, for example, as shown in Fig. 5.

In operation of the device, and assuming for example that the hose 4 is attached to the valve fitting 13 of the body structure, a suitable washing element 28 is secured to the plate 7 by means of the snap fasteners as aforesaid, and the cleaning and rinse liquids in the tanks 1 and 2 of the washing machine are placed under pressure by operation of the hand pump 3. The operator then picks up the washing device which is connected to the cleaning liquid hose by grasping the valve body 9 thereof with his hand and operates the lever 27 in the direction of the arrow in Fig. 4 to unseat the valve 17 and cause cleaning liquid to discharge through the port 21 and openings 22 and 31a into the sponge member 30 thereby wetting it. The device is then swept back and forth or up and down with the wet sponge cleaning element 30 in contact with the surface to be cleaned, and during the cleaning operation the rate of flow of cleaning fluid to the sponge 30 may be regulated and controlled at will in accordance with the requirements of the particular cleaning operation by manipulation of the valve lever 27. When the wall or other surface has been cleaned sufficiently, another of the washing devices 6 is attached to the rinse hose 5 and the cleaned wall is rinsed by using this other cleaning device in the manner just described. In some cases, it has been found desirable to en-

close the devices 6 within a bag or sack 34 of terry cloth or other similar soft yet rough-surfaced material.

From the foregoing it will be observed that the present invention provides a device of the type described wherein the flow of cleaning or rinse liquid to the scrubbing member may be controlled and regulated at will by the user without interrupting or interfering with the washing operation. Also, the novel construction and arrangement of the cleaning device permits of quick and easy attachment and detachment of the scrubbing members 28 with respect to the body structures of the washing device, and affords a better and more thorough cleansing action than prior devices of similar type.

While a particular embodiment of the invention has been illustrated and described herein, it is not intended to limit the invention to such disclosure, and changes and modifications may be made therein and thereto within the scope of the following claims.

I claim:

1. Washing apparatus comprising a substantially flat body member having an opening therethrough, a scrubbing and cleaning member having a substantially flat top surface, a backing overlying a portion of the top surface of the scrubbing and cleaning member and having therein an opening registering with the opening in said body member, means securing said backing and scrubbing and cleaning member together, separable fastener means having a part secured respectively to said backing and body member and detachably connecting the same together, a valve mechanism including a casing secured to the upper surface of the body member and constituting a hand grip for an operator to grasp and manipulate the washing apparatus, and a lever connected to said valve mechanism and extending laterally along one side thereof for actuation by a finger of the operator's hand to control the flow of liquid through the openings in the body member and backing to said scrubbing and cleaning member.

2. Washing apparatus comprising a substantially flat body member having an opening therethrough, a scrubbing and cleaning member having a substantially flat top surface and at least two opposite side portions, a flexible fabric backing overlying a portion of the top surface of the scrubbing and cleaning member and extending down partially over the two opposite sides thereof, means securing said backing and scrubbing and cleaning member together, separable snap-fastener means each having a part secured respectively to said backing and body member and detachably connecting the same together, a valve mechanism including a casing secured to the upper surface of the body member and constituting a hand grip for an operator to grasp and manipulate the washing apparatus, and a lever connected to said valve mechanism and extending laterally in position for actuation by a finger of the hand of the operator to control the flow of liquid through the openings in the body member and backing to said scrubbing and cleaning member.

3. Washing apparatus comprising a substantially flat body member having an opening therethrough, a scrubbing and cleaning member having a substantially flat top surface and at least two opposite side portions, a flexible fabric backing overlying a portion of the top surface of

the scrubbing and cleaning member and extending down partially over the two opposite sides thereof, said backing having an opening therein registering with the opening in said body member, means in the form of stitching passing through both said backing and scrubbing and cleaning member to secure the same together, separable snap-fastener means having a part secured respectively to said backing and body member and detachably connecting the same together, a valve mechanism including a casing secured to the upper surface of the body member and constituting a hand grip for an operator to grasp and manipulate the washing apparatus, and a lever connected to said valve mechanism and extending in position for actuation by a finger of the hand of the operator to control the flow of liquid through the openings in the body member and backing to said scrubbing and cleaning member.

4. Washing apparatus comprising a substantially flat body member having an opening therethrough, a scrubbing and cleaning member having a substantially flat top surface, a backing overlying a portion of the top surface of the scrubbing and cleaning member, said backing having an opening therein registering with the

opening in said body member, means to secure the backing and scrubbing and cleaning member together, separable snap-fastener means having a part secured respectively to said backing and body member and detachably connecting the same together, a valve mechanism including a casing secured to the upper surface of the body member and constituting a hand grip for an operator to grasp and manipulate the washing apparatus, and a lever connected to said valve mechanism and extending in position for actuation by a finger of the hand of the operator to control the flow of liquid through the openings in the body member and backing to said scrubbing and cleaning member.
